US0D1069989S

(12) **United States Design Patent** (10) Patent No.: **US D1,069,989 S**
(45) Date of Patent: ** Apr. 8, 2025

(54) **TAP**

(71) Applicant: **Zip Heaters (Aust) Pty Ltd**, Condell Park (AU)

(72) Inventors: **Anish Cherian Mathew**, Condell Park (AU); **David Mansueto**, Condell Park (AU)

(73) Assignee: **ZIP HEATERS (AUST) PTY LTD**, Condell Park (AU)

(**) Term: **15 Years**

(21) Appl. No.: **29/860,201**

(22) Filed: **Nov. 17, 2022**

(51) LOC (15) Cl. **23-01**

(52) U.S. Cl.

USPC **D23/238**

(58) **Field of Classification Search**

USPC D23/238-244, 252, 254-255, 257, 499;

D8/300, 307-308; D7/398

CPC F16K 31/602; F16K 31/605; F16K 31/607;

E03C 1/0412
